Patented Jan. 21, 1975

234,118

WORK HOLDING DEVICE

Thomas J. Molitors, Akron, Ohio, assignor to Karg
Machine Products, Inc., Tallmadge, Ohio

Filed Dec. 13, 1972, Ser. No. 314,755

Term of patent 14 years

Int. Cl. D8—05

U.S. Cl. D8—74

FIG. 1

FIG. 2

FIG. 3

FIG. 4

FIG. 5

FIG. 6

FIG. 1 is a perspective view illustrating a work holding device according to the invention;

FIG. 2 is a top plan view illustrating a work holding device according to the invention;

FIG. 3 is a side elevational view of a work holding device according to the invention;

FIG. 4 is an end view, taken substantially as indicated on line 4-4 of FIG. 3;

FIG. 5 is a cross-sectional view, taken substantially as indicated on line 5-5 of FIG. 3; and

FIG. 6 is an end view, taken substantially as indicated on line 6-6 of FIG. 3.

I claim:

The ornamental design for a work holding device, substantially as shown.
